UNITED STATES PATENT OFFICE.

FRANK W. GODFREY, OF BEAVERTON, OREGON.

VOTING-MACHINE.

1,080,006.

Specification of Letters Patent.

Patented Dec. 2, 1913.

Application filed April 15, 1911. Serial No. 621,312.

To all whom it may concern:

Be it known that I, FRANK W. GODFREY, a citizen of the United States, residing at Beaverton, in the county of Washington and 5 State of Oregon, have invented a new and useful Improvement in Voting-Machines, of which the following is a specification.

This invention relates to a voting machine.

10 The object of the invention is to facilitate the casting of votes, the automatic recording of the same and also to provide by means of suitable registering devices the number of votes cast for each candidate and 15 also the total number of voters voting.

A further object of the invention is to display publicly the total number of voters voting, thereby affording a check against successive voting by the same voter.

20 The invention consists in the novel features of construction hereinafter fully described, pointed out in the claims and shown in the accompanying drawings, in which,

Figure 1 is a front elevation of one of the 25 machines. Fig. 2 is a vertical transverse section. Fig. 3 is a section on the line 3—3 of Fig. 2. Fig. 4 is an enlarged detail sectional view, certain key levers and connecting mechanism being shown partly in elevation and partly in section. Fig. 5 is an 30 enlarged sectional view showing in elevation end portions of certain friction rollers.

In constructing the machine, which may be in various sizes, I employ a casing 1, 35 which casing is longitudinally slotted along its lower front portion as at 1^a in advance of the casing and projecting through said slot into said casing is a depressible platform 2, the inner end of which is normally 40 held in an elevated position by means of springs 3. It will be understood that the platform 2 in practice will be of such width that any one operating the machine will be compelled to step upon said platform and 45 it will also be understood that the machine may be arranged in a booth with the platform immediately within the drop curtain. To the upper central part of the casing I attach any suitable registering device 4, 50 which would of course be visible above any curtain which might screen the key board of the machine, and I at present contemplate employing registers of the Veeder type, already upon the market. The operating arm 5 of the register 4 is connected 55 to a transverse rod 6, which rod is pivotally

connected to the upper end of vertical bars 7, one of said bars being arranged adjacent an end of the casing. At the lower ends the bars are pivotally connected to the platform 2 and it will be obvious that every time the platform is stepped upon and depressed a record of such depression will be registered upon the register, and such registration will be visible to those in the room 65 in which the machine is placed.

Arranged at the rear of the machine is a roll of paper 8 and this paper travels beneath and then over a roller 9 passing between the roller 9 and a roller 10, the said 70 paper being drawn between the two rollers by frictional contact, and being fed upon a suitable shelf 11, which shelf forms the bottom of a compartment 12, said compartment being formed in the upper rear portion of 75 a casing for the purpose of holding the paper upon which the votes have been recorded.

The ends of the casing are suitably cut out as shown at 13, and in said cut out portions I mount rollers 14 covered by any suitable form of shield or closure device, and the rollers 14 carry a printing ribbon 15, operating upon the same principle as the inking ribbon found upon typewriting 80 machines, and said ribbon travels longitudinally along and immediately beneath the roller 9, which roller also serves as a platen, the paper traveling between said roller and the ribbon. The object of cutting out the 85 ends of the casing instead of placing the ribbon holders entirely within the casing is to facilitate renewal of the ribbons, and if desired any well known form of reversing mechanism may be employed in connection 90 with the rollers 14.

Key levers 16 carrying at their inner ends any suitable printing or stamping devices 17 and having keys 18 at their outer ends are journaled upon a transverse shaft 19 100 and project through a longitudinal slot 1^b formed in the front of the casing. Where a large number of keys are employed I prefer to offset them as shown in the drawings, although the arrangement of the keys is of 105 course a matter of convenience and is not material. The keys are normally held in elevated position by means of springs 20, and when depressed operate individual registering devices 21, each key being connected to one of these registering devices by a pivoted depending arm 22, which arm 1 110

have shown as working through the spring 20, although these springs may be connected and arranged in any manner desired so long as they will hold the keys in their normal positions, and return a key to normal position after it has been depressed and released.

To feed the paper step by step, I employ two pivoted bell cranks 23 and 24, connected together by a link 25, said bell cranks being arranged at one end of the casing and the bell cranks 23 are loosely connected to the bar 7, and the bell cranks 24 carry at their free short ends a spring pressed pawl 26 which engages a ratchet 26^a carried by one end of the roller 9. This drives the roller 9 step by step as the platform 2 is depressed and the rollers 9 and 10 are provided with intermeshing gears 27 as shown in Figs. 1, 3 and 5. The bell crank 24 also carries a spring pressed pawl 28 working at right angles to the pawl 26 and which engages a ratchet 29 upon one of the rollers 14, thus giving the roller a step by step rotation and winding the ribbon 15 thereupon, thus continually presenting a clean surface to the printing end 17 of the key levers.

In order to prevent a voter depressing a key more than once without leaving the platform I provide a rock shaft 30 extending longitudinally through the casing and beneath the keys, which shaft carries a plate 31 normally inclining downwardly and forwardly, and said shaft is rocked by means of arms 32 secured to the shaft and loosely pivoted to the bar 7. Each key is provided with a depending catch 33 normally held in engagement with the pawl 31 by a spring 34. As the platform is stepped upon the arms 32 will be drawn downwardly thus rocking the shaft 30 and throwing the plate 31 into the position shown in Fig. 4. Upon the depression of any key the catch 33, under pressure of its spring 34 will engage the lower edge of the plate, and will be locked in its depressed position until the voter has stepped from the platform thereby permitting the plate 31 to return to its normal position, thereby releasing all keys depressed and permitting the springs 20 to return them to normal position.

It will be understood that the paper may be ruled in any desired manner and that any kind of printing characters may be employed, as for example an "X", and the keys 18 are preferably numbered from one up, each number standing for some particular candidate whose name or a similar number will appear at the head of the column which would be imprinted upon by the depression of that particular key. As the first voter steps upon the platform the number 1 will appear upon the register 4, and each vote cast by him would be registered upon the individual registering devices 21,

the dials of which would be, of course closed against inspection by the voters. The voter could not depress the same key twice in succession thereby casting two votes for the same name, and he could not step from the platform in order to release the keys and again step back upon it without a second number appearing upon the dial 4, which dial is visible to all in the room.

What I claim is:—

1. A device of the kind described comprising a casing, the ends of said casing being cut out, a platen arranged in and parallel with the front of said casing, ribbon carrying rollers arranged in said cut out portions of the casing ends, means for covering said rollers and said cut-out portions, said means being arranged upon the exterior of the casing, a depressible platform, keys pivotally mounted within the casing and projecting through its front, the inner ends of said keys resting beneath said platen, means operated by depression of the platform for causing rotation of said platen and of said ribbon holders, thereby causing a sheet of paper to travel upon said platen and also cause a ribbon to travel from one of said rollers to the other, and means operated by depression of the platform for locking a depressed key until return of platform to normal position.

2. In a device of the kind described, a depressible platform, means for normally holding and returning said platform to an elevated position, a register, a vertical bar adapted to be moved downwardly by depression of the platform and operatively connected with said register, a depressible key, a rock shaft, a plate carried by said rock shaft, spring pressed catches carried by said keys, the said plate normally presenting an inclined face to said catches, means connecting said rock shaft to said vertical bar, thereby lifting said rock shaft and throwing the plate into a vertical position upon downward movement of the bar, depression of the key causing its catch to engage the lower edge of said plate.

3. In a voting machine, a vertically movable platform, said platform being normally held with its inner end elevated, vertically movable bars pivotally connected at their lower ends to the inner end of the platform, said bars being drawn downwardly when the platform is stepped upon, a registering device operated by downward movement of said bars, a series of key levers, springs for holding each key lever in normal position, a series of registering devices operatively connected to said key levers, a plate extending transversely beneath said key levers, a spring pressed hook member cooperating with said plate, the said plate and hook member being normally in inoperative position, the plate being thrown into

operative position by downward movement of the platform, and the hook member into engagement with said plate by depression of its key lever.

- 5 4. In a voting machine, a casing, rollers in frictional engagement with each other, a sheet of paper being adapted to travel under and over one of said rollers and between the two rollers and being fed by rotation of the
10 rollers, a compartment receiving said paper from the rollers, means for causing an inking ribbon to travel beneath said paper, intermeshing gears carried by said rollers, a ratchet carried by one of said rollers a
15 spring supported depressible platform, ver-

tical bars pivotally connected to said platform, a pair of bell cranks one of which is loosely connected to one of said bars, a link connecting the two bell cranks, a pawl carried by one of said bell cranks and engaging 20 the ratchet, said bell cranks being rocked by depression of the platform, and means also carried by the last mentioned bell crank for giving a step by step movement to the ribbon in unison with the rotation of the rollers, as and for the purpose set forth.

FRANK W. GODFREY.
